UNITED STATES PATENT OFFICE.

KAY N. RODGERS, OF PITTSBURGH, PENNSYLVANIA.

MUSIC-SHEET TURNER.

Application filed September 29, 1923. Serial No. 665,512.

To all whom it may concern:

Be it known that I, KAY N. RODGERS, a citizen of the United States, residing at Pittsburgh, in the county of Allegheny and 5 State of Pennsylvania, have invented certain new and useful Improvements in Music-Sheet Turners, of which the following is a specification.

This invention relates to music sheet turners for pianos and the primary object thereof is to provide a device of the type stated, which is foot-operated to turn a plurality of sheets in sequence as desired, and upon completion of the rendition return the sheets 15 to their original position; under such conditions permitting of the free use of the hands in rendering a composition without the usual interruptions necessitated by the employment of the hand for turning the 20 music sheets.

Further objects of the invention are to provide a device of the character described, in a manner as hereinafter set forth, which may be readily attached to a piano of the 25 usual construction without requiring additional materials except that embodied in the invention, which is simple in its construction and arrangement, strong, durable and efficient in its use, positive in its action, and 30 comparatively inexpensive to manufacture.

To the accomplishment of these and such other objects as may hereinafter appear, the invention consists of the novel construction, combination and arrangement of parts specifically described and illustrated in the accompanying drawing wherein is shown an embodiment of the invention, but it is to be understood that changes, variations, and 35 modifications may be resorted to which come 40 within the scope of the claim hereunto appended.

In the drawing forming a portion of this specification and wherein like numerals of reference designate corresponding parts 45 throughout the several views:—

Figure 1 is a top plan view of a music sheet turner in accordance with my invention.

Figure 2 is a side view thereof with the 50 casing shown in cross section.

Figure 3 is a diagrammatic view illustrating the relative position of the operating drum with respect to the arm carrying plates and associated parts.

Figure 4 is a side view of the sheet clamp. Referring in detail to the drawing 1 de-

notes a casing provided adjacent to its upper end with a pair of transversely disposed cross-bars 2 and 3, respectively.

A vertically disposed shaft 4 is fixedly 65 mounted in the casing 1, adjacent to the rear end thereof. The lower end of the shaft 4 is mounted in the bottom of the casing 1 and its upper end engages in the cross-bar 2.

Rotatably mounted on the vertical shaft 4 is a drum 5 and a disk wheel 6. The former is positioned below the latter on the vertical shaft 4 and is provided on its lower face with ratchet teeth 7. A resilient pawl 8 is mounted on the bottom of the casing 1 and engages the ratchet teeth 7 of the drum 5, as clearly illustrated in Figure 2, of the drawing. The engagement of the pawl 8 with the ratchet teeth 7 permits of the rotation 75 of the drum 5 only in the counter clockwise direction.

The disk wheel 6 is likewise provided on its lower face with ratchet teeth 9 which are engaged by a resilient pawl 10 mounted 80 on the top face of the drum 5. The ratchet teeth 9, of the disk wheel 6, are disposed in the opposite direction relatively to the disposition of the ratchet teeth 7 carried by the drum 5.

A coil spring 11 is mounted on the top of the wheel disk 6. One end of the spring 11 is fixed to the hub of the wheel disk 6 and the other end thereof is fixed to a post 12 mounted in the casing 1. The action of 85 the coil spring 11 normally tends to rotate the disk wheel 6 in the clockwise direction.

The disk wheel 6 is formed with a peripheral groove 12' in which a flexible pull member 13 is positioned. The pull member 13 has one end thereof secured in the groove 12' and extends only part way around in the groove 12'. The other end of the pull member 13 extends rearwardly 95 through an aperture 14 formed in the casing 100 1, and is connected with the link 15.

A substantially V-shaped operating lever 16 is pivotally connected, as at 17, to a bracket 18, mounted on a bottom extension 19 of the casing 1. One leg of the lever 16 is pivotally connected to the link 15, and the other leg thereof is pivotally connected, as at 20 to the top of the actuating rod 21. The lower end of the latter is adapted to be connected with a treadle which is positioned to suit the 110 convenience of the operator.

It will be noted that the flexible pull

member 13 is engaged in the groove 12, of the disk wheel 6, in a manner so that a rearward pull on the member 13 will rotate the disk wheel 6 in the counter clockwise direction for the purpose to be described.

The forward wall of the casing 1 is formed with an opening 22 in which is mounted upper and lower brackets 23 which support a vertical fixed shaft 24 in a manner to position the latter forward of the front end of the casing 1.

Rotatably mounted on the fixed vertical shaft 24 is a pair of annular plates 25 and 26, respectively. The plate 25 is positioned above the plate 26, and each carries a coil spring 27 having one end attached to the front wall of the casing 1, as indicated at 28, and the other end thereof to the hub of respective annular plates 25 and 26. The action of the spring 27 normally tends to turn associated plates 25 and 26 in the clockwise direction.

Each of the plates 25 and 26 carries a turning arm 29 fixed thereto to the outer end of which a sheet clamp 30 is swivelly mounted, as shown at 31, in Figure 5, of the drawing. Each of the plates 25 and 26 is further provided with a recess 32, formed on its periphery, for the purpose to be described.

A vertically disposed fixed shaft 33, secured at its lower end to the bottom of the casing 1 and at its upper end to the cross-bar 3, is mounted in the casing 1 adjacent to the forward end thereof. Rotatably mounted on the shaft 33 is a gear 35. The latter carries a coil spring 36 having one end attached to the hub thereof and the other end to a post 37 fixed in the casing 1. The gear 35 is in mesh with a pinion 38 rotatably mounted on the upper end of the fixed vertical shaft 24. The pinion is provided with a short projecting arm 39 having a depending rod 40 fixed in its outer end. The action of the spring 36 normally tends to rotate the gear 35 in the counter clockwise direction and in consequence the pinion 38, in mesh with the latter, will turn in the clockwise direction. Such rotary movement of the pinion 38 and associated gear 35 is limited by the contacting of the arm 39 with the front wall of the casing 1.

Fixedly mounted in the casing 1 is a short vertical shaft 41 upon which a pair of trip levers 42 and 43 are pivotally mounted, as indicated at 44. The forward end of the lever 42 is arranged to travel on the periphery of the annular plate 25 and engage in the recess 32 formed therein, and the forward end of the lever 43 is arranged to travel on the periphery of the annular plate 26 and engage in the recess 32 formed therein. A spring 45 is attached to each of the levers 42 and 43 and to a post 46 mounted in the casing 1. The action of the

springs 45 hold the levers 42 and 43 in engagement with the periphery of respective annular plates 25 and 26.

Each of the levers 42 and 43 is provided with a laterally disposed angular end 47. The end 47 of the lever 42 is arranged in the path of travel of an actuating pin 48, and the end 47 of the lever 43 is arranged in the path of travel of the actuating pin 49. The pins 48 and 49 are radially fixed in the periphery of the drum 5 and are provided with V-shaped outer ends. In like manner an actuating arm 50 is fixed on the periphery of the drum 5 to engage the depending leg 51 fixed to the lower face of the gear 35 adjacent to its periphery for the purpose to be described.

It will be noted that the pin 48, the pin 49 and the arm 50 are equally spaced from each other on the periphery of the drum 5.

In practice the operation of the device is as follows:—

The device is positioned centrally on top of the piano with the parts thereof substantially in the positions as shown in Figure 2, of the drawing. The actuating rod 21 is attached to a suitable treadle (not shown) accessible to the operator. Assuming there are two sheets to be turned, the clamp 30 associated with the annular plate 25 is secured to the marginal upper edge of the first sheet, and the clamp 30 associated with the annular plate 26 is attached to the marginal top edge of the second sheet. When it is desired to turn the first sheet the operator, by depressing the treadle, will actuate the lever 16 whereby the pull member 13 is drawn rearwardly rotating the disk wheel 6 in the counter clockwise direction. The engagement of the pawl 10 with the ratchet teeth 9 on the disk wheel 6 will likewise cause the rotation of the drum 5 in the counter clockwise direction.

Upon rotation of the drum 5, as above stated, the pin 48 carried thereby will engage and shift the lever 42 causing the latter to disengage the recess 32 of the annular plate 25. The annular plate 25 being released, the action of its spring 27 will cause the rotation of the plate 25 in the clockwise direction together with its associated turning arm 29 and the first music sheet attached thereto. The rotation of the plate 25 in the clockwise direction will stop when the associated arm 29 strikes the depending rod 40 and the sheet has been properly turned over.

After the first sheet turning operation is described the operator releases the treadle allowing the spring 11 to return the wheel disk 6 to its original position by rotating it in the clockwise direction. The arrangement of the pawl 10 and ratchet teeth 9 will permit of such return movement of the wheel disk 5, but the arrangement of the

pawl 8 and ratchet teeth 7 will prevent the rotation of the drum 5 in the clockwise direction.

It will be noted that after the first sheet turning operation the pin 48 will have cleared the lever 42 and moved the pin 49 in position to engage the lever 43 upon the next depression of the treadle to operate the actuating rod 21 and the lever 16.

10 The second depression of the treadle will cause the pin 49 to engage and shift the trip lever 43 to release the annular plate 26 thereby permitting its spring 27 to move the associated turning arm 29 to turn the second music sheet in a manner identical to that described relative to the first sheet turning operation.

Both of the turning arms 29 will now be positioned against the depending rod 40 and the arm 50, carried by the drum 5, is in position to engage the depending leg 51 of the gear 35.

20 The third depression of the treadle will cause the arm 50 to engage the leg 51 rotating the gear 35 in the clockwise direction and the pinion 38 in mesh with the gear 35 in the counter clockwise direction. As the depending rod 40 is connected with the pinion 38 through the arm 39, the turning arms 29 will be returned to their original positions, as the arm 50 clears the leg 51, together with the music sheets attached thereto.

25 The action of the springs 45 will hold the outer ends of the levers 42 and 43 against the peripheries of the respective annular plates 25 and 26, and when the latter are returned to the original positions as above stated the outer ends of the levers 42 and 40 43 will again engage in the recesses 32 of respective annular plates 25 and 26 thereby locking them in the original position and tensioning their springs 27, and positioning all parts of the device in their original positions permitting a repetition of the entire operation as above described.

While describing and illustrating a device capable of turning two sheets of music be-

fore returning them to their original positions it will be obvious that the device may 50 be readily provided to turn a plurality of sheets by providing a corresponding number of annular plates and turning arms with associated operating mechanism in accordance with the principle involved in the embodiment described and illustrated.

55 What I claim is:—

In combination, a device for the purpose set forth comprising a casing provided with a rear bottom extension, a substantially V- shaped operating lever pivotally mounted on said extension and adapted to be connected with a treadle, a pair of annular plates rotatably mounted in the forward end of said casing, each of said plates formed with a peripheral recess and carrying a turning arm provided at its outer end with a swivelly connected sheet clamping member, each of said plates associated with a spring element for shifting said arm in the clockwise direction, a drum mounted in said casing and capable of rotation in the counter clockwise direction, a disk wheel rotatably mounted in said casing, means carried by said drum and engaging said wheel for intermittently revolving said drum during the operation of said wheel, a flexible member connected with said wheel and with said operating lever for partially rotating said wheel when said operating lever is actuated, a spring element for returning said wheel to the operative position, a pair of trip levers adapted to engage in said recesses of said plates for securing said arms in the initial position, means carried on the periphery of said drum and adapted to engage said trip levers for consecutively releasing said plates for shifting said arms, and means actuated by the rotation of said drum for returning said arms to the initial position, substantially as described and for the purpose set forth.

70 75 80 85 90 In testimony whereof I affix my signature.

KAY N. RODGERS.
